UNITED STATES PATENT OFFICE

ALEXANDER J. DOMBROWSKI, OF NESHKORO, WISCONSIN

ADJUSTABLE SNOWPLOW SHOE

Application filed July 12, 1932. Serial No. 622,124.

This invention relates to certain new and useful improvements in adjustable snow plow shoes.

The primary object of the invention is to provide an adjustable snow plow shoe wherein the ground engaging skid portion of the shoe is adjustable relative to a carrying section to compensate for wear on the shoe with the adjustment accomplished in a minimum of time and labor with the shoe construction and adjusting elements of a character whereby the ground engaging portion of the shoe is rigidly maintained in adjusted position against accidental displacement with the entire adjustment accomplished without the necessity of removing the shoe from the plow.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a top plan view of a snow plow shoe constructed in accordance with the present invention;

Figure 2 is a side elevational view showing the ground engaging portion of the shoe projecting below a carrying section or backing member;

Figure 3 is a vertical longitudinal sectional view taken on line 3—3 of Figure 1, showing the screw operated cam devices to effect adjusting movement of the ground engaging portion of the shoe with the anchor bolt for attaching the shoe to the plow having the heads thereof countersunk in the backing of the shoe;

Figure 4 is a cross-sectional view taken on line 4—4 of Figure 2; and

Figure 5 is a detail sectional view showing another form of bolt connection between the shoe and plow.

Referring more in detail to the accompanying drawing, there is illustrated a snow plow shoe comprising a backing 10 and a ground engaging shoe portion 11. The backing 10 is of casing-like formation having a top wall

12, depending side walls 13 and end walls 14. Bolts 15 for anchoring the shoe to the plow have the heads 16 thereof counter-sunk in the top wall 12 of the backing with the lower ends of the heads 16 flush with the bottom face of the top wall 12 as shown in Figure 3.

The shoe 11 comprises an elongated block 17 neatly fitting within the depending side and end walls of the backing member 10 for sliding adjustment therein and having its lower ground engaging edge 18 projecting below the side and end walls of the backing. The ground engaging shoe 11 is retained in the backing 10 by means of transversely extending screw bolts 19 freely passing through openings 20 in the shoe 17 and also through the vertically extending slots 21 in the side walls 13 of the backing, the ground engaging shoe 17 being retained in vertically adjusted positions relative to the backing 10 by means of washers 22 and nuts 23 associated with the screw bolts 19 as shown in the several figures.

The adjustment of the ground engaging shoe 17 for movement outwardly of the backing 10 to compensate for wear is accomplished by screw operated cam devices consisting of a screw shaft 24 extending through the cut-out portion 25 in the upper end of the ground engaging shoe 17, having opposite ends thereof oppositely threaded as at 26 and freely passing through openings in the end walls 14 of the backing with a head and washer combination 27 upon one end of the screw shaft 24 while the other end of the screw shaft carries a key extension 28 to receive a tool to effect manipulation thereof and also a jamb nut 29 to hold the screw shaft against rotation. The upper face of ground engaging shoe 17 at each end thereof is provided with an inclined cam face 30 engaged by a cam block 31 threaded upon the adjacent threaded end 26 of the screw shaft 24 as shown in Figure 3 so that when the jamb nut 29 is released from engaging with the adjacent end wall 14 of the backing and a tool or other implement applied to the key end 28 of the screw shaft 24, the latter is rotated for moving the cam blocks 31 toward each other over the cam surfaces 31 of the ground engaging shoe to effect lowering

movement of the latter or movement thereof outwardly of the backing to present a greater exposed section of the ground engaging shoe with respect to the backing to compensate for wear of the ground engaging shoe. When the screw shaft 24 is being operated, the transversely extending bolts 19 have the retaining nuts 23 thereof loosened so that the ground engaging shoe may be easily extended and when proper adjustment has been accomplished, the nuts 23 are again tightened for holding the ground engaging shoe in its adjusted position.

The bolts 15 for attaching the shoe to the snow plow have been illustrated and described in Figures 1 to 4 as having the heads 16 thereof counter-sunk in the top wall 12 of the backing while another form of bolt mounting is illustrated in Figure 5. The top wall 12 of the backing as shown in Figure 5 has a relatively small plate section 32 welded or otherwise secured thereto as at 33 with the head 16a of the bolt 15a counter-sunk in the plate 32. In the event of breakage of the bolts 15a, it would only be necessary to remove the plate 32 from the backing plate 12 without disturbing the operating devices for the ground engaging shoe 17, a new anchor bolt and attaching plate being substituted in a minimum of time.

From the above detailed description of the invention, it is believed that the construction and operation thereof will at once be apparent, and while there are herein shown and described the preferred embodiments of the invention, it is nevertheless to be understood that minor changes may be made therein without departing from the spirit and scope of the invention as claimed.

40 I claim:—

1. In an adjustable snow plow shoe, a backing, a ground engaging shoe adjustable therein and means for adjusting the shoe relative to the backing including a screw shaft, cam blocks thereon and cam faces on the shoe engageable by the blocks to effect movements of the shoe outwardly of the backing.

2. In an adjustable snow plow shoe, a backing, a ground engaging shoe adjustable therein, means for adjusting the shoe relative to the backing including a screw shaft, cam blocks thereon and cam faces on the shoe engageable by the blocks to effect movements of the shoe outwardly of the backing, and transversely extending bolts carried by the ground engaging shoe for anchoring the latter in adjusted position to the backing.

3. In an adjustable snow plow shoe, a backing, a ground engaging shoe adjustable therein, means for adjusting the shoe relative to the backing including a screw shaft, cam blocks thereon and cam faces on the shoe engageable by the blocks to effect movements of the shoe outwardly of the backing, and bolts

carried by the top of the backing for securing the shoe to a snow plow.

4. In an adjustable snow plow shoe, a backing, a ground engaging shoe adjustable therein, means for adjusting the shoe relative to the backing including a screw shaft, cam blocks thereon and cam faces on the shoe engageable by the blocks to effect movements of the shoe outwardly of the backing, transversely extending bolts carried by the ground engaging shoe for anchoring the latter in adjusted position to the backing, and bolts carried by the top of the backing for securing the shoe to a snow plow.

5. In an adjustable snow plow shoe, a backing, a ground engaging shoe adjustable therein, means for adjusting the shoe relative to the backing including a screw shaft, cam blocks thereon and cam faces on the shoe engageable by the blocks to effect movements of the shoe outwardly of the backing, bolts carried by the top of the backing for securing the shoe to a snow plow, the connection between the last named bolts and backing including plates secured to the top of the backing with the heads of the bolts countersunk in the plates above the top of the backing.

6. In an adjustable snow plow shoe, a backing, a ground engaging shoe adjustable therein, means for adjusting the shoe relative to the backing including a screw shaft, cam blocks thereon and cam faces on the shoe engageable by the blocks to effect movements of the shoe outwardly of the backing, transversely extending bolts carried by the ground engaging shoe for anchoring the latter in adjusted position to the backing, bolts carried by the top of the backing for securing the shoe to a snow plow, the connection between the last named bolts and backing including plates secured to the top of the backing with the heads of the bolts countersunk in the plates above the top of the backing.

7. In an adjustable snow plow shoe, a backing, a ground engaging shoe adjustable therein, means for adjusting the shoe relative to the backing including a screw shaft, cam blocks thereon and cam faces on the shoe engageable by the blocks to effect movements of the shoe outwardly of the backing, the backing including a top wall, end walls and side walls with the ground engaging shoe confined within the walls, and said screw shaft extending through the end walls and disposed above the ground engaging shoe.

8. In an adjustable snow plow shoe, a backing, a ground engaging shoe adjustable therein, means for adjusting the shoe relative to the backing including a screw shaft, cam blocks thereon and cam faces on the shoe engageable by the blocks to effect movements of the shoe outwardly of the backing, transversely extending bolts carried by the ground engaging shoe for anchoring the latter in adjusted position to the backing, the backing

including a top wall, end walls and side walls with the ground engaging shoe confined within the walls, and said screw shaft extending through the end walls and disposed above the ground engaging shoe.

5 In testimony whereof I affix my signature.

ALEXANDER J. DOMBROWSKI.
